United States Patent Office

Des. 197,630
Patented Mar. 3, 1964

197,630

BOTTLE

Donald A. Hill, Arcadia, Calif., assignor to Hill Brothers Chemical Company, City of Industry, Calif., a corporation of California

Filed June 28, 1963, Ser. No. 75,573

Term of patent 14 years

(Cl. D58—6)

FIGURE 1 is a perspective view of the bottle showing my new design;

FIGURE 2 is a side elevation thereof;

FIGURE 3 is a front elevation thereof;

FIGURE 4 is a rear elevation thereof;

FIGURE 5 is a top plan view thereof; and

FIGURE 6 is a bottom plan view thereof.

I claim:

The ornamental design for a bottle, substantially as shown.
